(57) **CLAIM**

The ornamental design for a semi-truck body, as shown and described.

DESCRIPTION

FIG. 1 is a top, front, left side perspective view of a semi-truck body showing our new design;

FIG. 2 is a top, rear, right side perspective view thereof;

FIG. 3 is an enlarged front elevation view thereof;

FIG. 4 is an enlarged rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" (identified in FIG. 1), shown at a greater scale for clarity of disclosure;

FIG. 10 is an enlarged view of detail "10" (identified in FIG. 1), shown at a greater scale for clarity of disclosure;

FIG. 11 is an enlarged view of detail "11" (identified in FIG. 1), shown at a greater scale for clarity of disclosure;

FIG. 12 is an enlarged view of detail "12" (identified in FIG. 1), shown at a greater scale for clarity of disclosure;

FIG. 13 is an enlarged view of detail "13" (identified in FIG. 2), shown at a greater scale for clarity of disclosure;

FIG. 14 is an enlarged view of detail "14" (identified in FIG. 2), shown at a greater scale for clarity of disclosure;

FIG. 15 is an enlarged view of detail "15" (identified in FIG. 1), shown at a greater scale for clarity of disclosure; and,

FIG. 16 is an enlarged view of detail "16" (identified in FIG. 1), shown at a greater scale for clarity of disclosure.

The broken lines shown in the drawings depict portions of the semi-truck body that form no part of the claimed design. The dot-dash broken lines represent boundaries of the enlarged portions and form no part of the claimed design. None of the elements shown in broken lines form a part of the claimed design.
